US00D380302S

United States Patent [19]

Volpenhein

[11] Patent Number: Des. 380,302

[45] Date of Patent: **Jul. 1, 1997

[54] SET OF BRISTLES

[75] Inventor: Daniel William Volpenhein,
Maineville, Ohio[73] Assignee: The Procter & Gamble Company,
Cincinnati, Ohio

[**] Term: 14 Years

[21] Appl. No.: 39,051

[22] Filed: May 19, 1995

[51] LOC (6) Cl. 04-02

[52] U.S. Cl. D4/104

[58] Field of Search D4/101, 104-112,
D4/114-120, 130, 132-134, 136; 15/22.1,
22.2, 159.1, 160, 167.1, 167.2, 186, 187,
DIG. 5, DIG. 6; 132/308, 309, 311; 601/137,
139-142

Attorney, Agent, or Firm—Michael J. D'Amelio; Ronald W. Kock

[57] CLAIM

The ornamental design for a set of bristles, as shown and described.

DESCRIPTION

FIG. 1 is a perspective view of a set of bristles embodying my new design;

FIG. 2 is a top view thereof;

FIG. 3 is a front elevational view thereof;

FIG. 4 is a left side elevational view thereof, the right side elevational view being a mirror image of the left side elevational view; and,

FIG. 5 is a rear elevational view thereof.

The broken lines are for illustrative purposes only and form no part of the claimed design.

1 Claim, 2 Drawing Sheets
